William Birds Springfield N. Y.

Setters Patent

The subscriber refers to in this Setters Patent and Marks his joint invention containing a description in the words of the late William Birds himself of his improvement to the Markers for punishing and breaking Wheel loops or tires.

To all to whom these presents shall come be it known that I William Birds of Springfield in the County of Ulster in State of New York have invented a new and useful machine for punishing and breaking wheel loops or tires and that the following is a full and true description of the construction and operation of said machine as invented or improved by me: The machine is of the form of a frame, one part or principle for punishing, the other for breaking. The part of the machine for punishing is made of iron or other metal to pieces of which the wheel tire and guides are connected together at the ends by strong bolts and nuts, the pieces being particularly through the ends of each end, nail, bolt and iron rail. The rods and guides are about $\frac{1}{2}$ inch ^{each} long and from 1 to 1 $\frac{1}{2}$ inches wide, with a corresponding hole about one inch in diameter passing perpendicularly through the center of each the guides being half an inch wide and a half inch thick and the base is from 16 to 18 inches deep with a box about 16 inches wide and half inch deep situated over the hole in the center of the base for the reception of rods of the same size of the box made of steel or iron faced with steel through the center of which is a hole same size of the base hole to be punched.

The punishing wheel loops or tires or any thick iron or iron and different punches are alternately set in punishing each hole. The punches are made of steel from 3 to 5 inches long about 1 inch in diameter like common spurs at the pointed end like the base end of a cylinder except that the points of the punches are set back from the base $\frac{1}{4}$ to $\frac{1}{2}$ of an inch to leave the point at the corner or base end. The punches are made in the base box to be used like those now in common use. The machine may also be used for breaking punishing holes of different sizes in soft iron thin iron or steel or iron

146

sets of the racing principles of different sizes made on the principle of those above described and also with holes of different sizes in them to fit into some Machine. Machines to punch out holes of any size only may be made small or would
size by making the hole through the ball. The size of the hole to be punched
and facing it with steel instead of letting it a die. The other part of this
machine by which the hoofs or tires are bent is a bar set which segments
of different circles are attached and attached by means of an iron bolt to be kicked
long. The bar is from 5 to 8 feet long, and but 16 inches of which goes to the handle.
The handle part of the bar which may be called the segment bar on which the
segments are attached and attached is 16 inches long and from 3 to 4 inches
thick. A straight line drawn through on the upper side of the handle intersects
the segment bar at the end of the bar and with it and an angle of about 27
degrees. The end of the bar is bent back towards the handle 1/4 inches to a
curve on the outside of the segment bar. The bar is about 6 1/2 inches thick at
the end and is the same width 16 inches back on the segment bar where the iron
bolt goes through it. On top of the bar between the curve and the place where
the iron bolt goes through it is a curve on a circle whose radius is 12
inches and joined with this iron. Inside the end of the bar is a stamping
box of iron containing prongs below the bar to receive the end of iron to be
bent and is kept in its place by short spikes driven into the bar on each side of
it. Inside this iron stamping is raised up by putting them iron into the
upper part of it. The segments are made of hard timber 16 inches long, some
twisting of the bar. 2 1/4 inches deep, where the bolt goes through them and
half inch deep or thick at the end to go under the stamping with a hole 1/2
inches, you can then 6 to 8 iron short pins in the bar which is also made
of hard timber. Owing to the elastic nature of iron segments are made
from 16 inches to 20 inches and 22 inches and 24 inches long, so
that when pushed in it is wider than the diameter of the wheel for which
the hoofs or tires are to be bent. In the method of making the part of
the machine is to make as many different bars as there are segments
of different circles required in the part described above which will probably
never exceed 16 inches and when the stamping is made here to the other method
of lifting the segments. The bars when made are on the same shape

and from that the other pieces are usually in which the different segments are
separately attached to it. The bars or bars are operated between a stock of timber
about 16 feet long & 6 1/2 inches square and an iron pin which is
about a stick of 10 inches about said stick of timber into which the stick is driven
short from one end. On the bars or bars may be operated smaller iron pins which
are any convenient part or place about the body of timber.

The following of this machine
is the practice and action from old without heating, to which the iron
shall be heated, place the iron into the machine between the bar and guide and
drive it by turning the handle. Then place the machine on an anvil and the
punch having heated drive into the hole in the guide and drive it in the
middle of the first with a wedge. Next drive in the other punch until the same
principle and the hole will be so far punched out the iron to punch broken
that it may be finished with the old fashioned punch lightly drive with a
wedge or hammer. The point of punches should be kept filed while using them
so that the hoop or wire to place the bar of iron under the fire and
place the stones over the end of the iron after attaching the proper segment to
the bar in the bar is made on the plan, not deviated and turn it under
the iron pin and it will bend the iron to the circle of the iron ~~pin~~ a
segment in the bar, then can repeat and draw the bar back to the straight
part of the bar and while the bar and iron under the iron pin and turn
the bar as before and so on repeating the same operations until the hoop
is like a belt. If the iron with little elasticity in it, will be bent too crooked
at the times which may be easily straightened to the right circle by placing
the side of a wedge under the hoop or wire and heating the outside with
a hammer.

The invention of the machine on the different principles
specified and described (except the old fashioned punch to be used in
the same) is claimed
